UNITED STATES PATENT OFFICE.

WILTSIRE SANDERS AND JOHN BENJAMIN RAFFERTY, OF RENO, NEVADA.

BIER.

SPECIFICATION forming part of Letters Patent No. 450,894, dated April 21, 1891.

Application filed September 15, 1890. Serial No. 365,088. (No model.)

To all whom it may concern:

Be it known that we, WILTSIRE SANDERS and JOHN BENJAMIN RAFFERTY, of Reno, in the county of Washoe and State of Nevada, ⁵ have invented a new and useful Improvement in Biers, of which the following is a specification.

Our invention is an improvement in the class of folding or collapsible biers, more especially such as are provided with casters or other form of wheels for adapting them to be more easily moved from place to place.

The novelty consists in the construction and combination of parts, as hereinafter described ¹⁵ and claimed.

In the accompanying drawings, Figure 1 is a perspective view of our bier extended in position for use. Fig. 2 is a perspective view showing one end portion folded upon the other, ²⁰ which remains in the original horizontal position. Fig. 3 is also a perspective view showing the parts folded as compactly as possible. Fig. 4 is a perspective view illustrating a detail.

²⁵ The main frame of the bier is rectangular and oblong. The parallel side bars are connected rigidly by means of a transverse bar *b* and iron rods *c*. The said side bars are divided transversely at the middle of their

³⁰ length and flexibly connected at that point by means of strong strap hinges *d*, which are so applied as to permit one portion of the bier to be folded over upon the other, as shown in Fig. 2. Thus, as will be seen, the bier is com-

³⁵ posed of two main folding parts. The side bars *a a* of one such part are supported at their inner ends by two hinged folding legs *e e* and at their outer ends by a single folding leg *f*, which is rigidly attached to a transverse

⁴⁰ roller *g*, journaled in said side bars. The other folding part of the bier is supported at its inner end by the hinges *d* and at its outer end by a folding leg *f'*, which, like the other folding leg *f*, is connected with the side bars *a' a'* by a roller *g'*.

⁴⁵ The means for holding the folding legs *f f'* rigid in the upright position are as follows: Each of the legs is connected by a bifurcated brace *h* with a transverse bar *i*, whose rectangular ends enter and slide in grooves *j*, formed longitudinally in the inner sides of both sets of side bars *a a' a' a*. The braces

⁵⁵ *h* are loosely jointed to the said bars, so that each of the latter may be turned or rotated on its axis, in order to lock it in a depression or downward extension formed at the outer end of each groove *j*—that is to say, when the bars *h* are turned to bring their sides parallel with the sides of the grooves they will slide along the latter, and thus allow the legs *ff'* ⁶⁰ to be folded, Fig. 3; but when turned, say one-quarter around, the said bars *h* engage the shoulders of the terminal depressions of the grooves *j*, Figs. 1 and 4, and are thus prevented from sliding along the grooves *j*. As ⁶⁵ shown in the drawings, the braces *i* are connected with the bars *h* by means of loops passing through holes in the latter. It is obvious various modes of loose connection of these parts might be adopted with the same result. ⁷⁰ The legs *e e* are provided with pivoted braces *h'*, having a rule-joint.

As shown in Fig. 1, the part composed of side bars *a a'* and leg *f'* is folded and rests on the other part having the rigid legs *e* and the folding leg *f*. The bier is then tilted to bring the bars *a a'* and *a' a'* into vertical position, as shown in Fig. 3, when the legs *e* and *f* are also folded. The bier is then in compact form, as required for storage or transportation. ⁸⁰

The several folding legs are provided with casters *k*, thus converting the bier into a truck, which may be easily moved about even when supporting a corpse. ⁸⁵

We provide the bier with trays *l* for supporting candles, bouquets, or other objects which it may be desired to place beside the corpse. Each tray is attached to a right-angled rod *m*, whose vertical arm enters a socket ⁹⁰ in a side bar *a* or *a'*.

When in use, the trays *l* are turned outward, so as to project laterally from the body of the bier, as shown in Fig. 1; but when the bier is folded, as in Figs. 2 and 3, the trays ⁹⁵ are turned inward and held in such position by means of hooks *n*, that are pivoted to the inner sides of the bars *a* and *a'* and engage the horizontal arms of the rods *m*. To further secure the said rods, their horizontal arms ¹⁰⁰ may be let into shallow grooves in the side bars, as shown.

What we claim is—

1. In a bier, the combination, with the frame

side bars having internal longitudinal grooves, of a hinged and folding leg, the brace therefore, and a transverse bar whose rectangular ends enter the said grooves and are adapted 5 to slide or lock therein according as the bar is turned or adjusted, as specified.

2. The combination, with the frame of the bier, of the trays and their angular support- rods which enter sockets in said frame,

and the pivoted hooks adapted to engage the rods and hold the trays locked in the folded position, as specified.

WILTSIRE SANDERS.
JOHN BENJAMIN RAFFERTY.
